W. G. BUCK

ROTATOR FOR VALVES OF INTERNAL COMBUSTION ENGINES

Filed March 13, 1918

Inventor:
Wilmer G. Buck
by: J. M. Bond Atty.

UNITED STATES PATENT OFFICE.

WILMER G. BUCK, OF FREMONT, NEBRASKA, ASSIGNOR TO CONTINENTAL ENGINEERING CORPORATION, OF OMAHA, NEBRASKA, A CORPORATION OF NEBRASKA.

ROTATOR FOR VALVES OF INTERNAL-COMBUSTION ENGINES.

Application filed March 13, 1918. Serial No. 222,119.

To all whom it may concern:

Be it known that I, WILMER G. BUCK, a citizen of the United States, residing at Fremont, in the county of Dodge and State of Nebraska, have invented certain new and useful Improvements in Rotators for Valves of Internal-Combustion Engines, of which the following is a specification.

The present invention relates to a device for imparting a rotative movement to a predetermined degree to the puppet valve of an internal combustion engine, and is based upon the general principle disclosed in my United States Patent No. 1,183,852 of May 15, 1916, and United States Patent No. 1,244,287 of October 23, 1917.

The general object of the invention is to provide means for imparting a rotative movement to the valve stem and valve while the said parts are moving in one direction.

A further object of the invention is to provide a simple and efficient means for attaching the device to the stem of the ordinary valve, whereby practically no change is necessitated in the construction of such stem nor any weakening thereof.

A further object of the invention is to construct and arrange the parts which produce the rotative movement so that the amount of friction between them is reduced to a small degree.

A further object of the invention is to expose the parts for producing the rotative movement so that they may readily receive oil during the running of the engine and thus be kept in the desired state of lubrication.

The invention further consists in the features of construction and combination of parts hereinafter described and claimed.

In the drawings:

Figure 1 is a cross section through a portion of an engine casing, showing one of the piston chambers and one of the valve chambers with the rotator of the present invention in operating position;

Figure 2 is an enlarged cross section through the rotator mechanism;

Figure 3 is a plan view;

Figure 4 is a section on line 4—4 of Figure 2; and

Figure 5 is an under face view of the connection between the valve stem and rotator device.

Referring now to the drawings, the invention is illustrated in connection with a gas engine, which may be of any suitable size and style. A casing 4 is illustrated, containing a piston 5, a piston chamber 6, push-rod chamber 7, piston rod 8, and a valve tappet actuating cam 9. All of the above may be of any suitable type of construction.

As shown, there is a passage 10 between the valve chamber and the chamber in which the crank shaft (not shown) operates. Oil may pass through this opening and become vaporized in the chamber 7 by the heat therein. This has to do with the lubrication of the rotator mechanism, as will be hereinafter explained. The said rotator mechanism is applied to a valve stem 11, which carries upon its upper end the ordinary puppet valve 12 resting upon the usual seat 13. The said valve may be of such style and size as desired.

The rotator mechanism consists of a sleeve 14 terminating in a head 15, which is grooved to provide a ball-race 16. Upon its outer face, the head is recessed as at 17, and resting within said recess is a horseshoe key 18, which straddles the valve stem, said stem being flattened on each side to receive said key. This method of connecting the valve stem and head 15 of the rotator device makes said connection firm and rigid, and eliminates any boring of holes in the valve stem, which might weaken the structure thereof. Merely flattening each side of the stem in the manner shown does not weaken the same, and is a very quick and easy manufacturing operation. The recess 17 is of an elongated nature so that any rotative movement imparted to the sleeve 14 will be transmitted to the valve stem 11 by the elongated connection therebetween.

Positioned above the head 15 is a ring 19, having formed therein a ball-race 20, and traveling within said races 16 and 20 are balls 21. This ring 19 is secured to the sleeve 14 in any suitable manner, as, for instance, by a collar 22 put on with a driving fit.

The sleeve 14 terminates at its upper end in a toothed clutch surface 23. Positioned above the sleeve 14 is a sleeve 24 loose upon the valve stem, and for the purpose of clearness in description, the sleeve 14 may be referred to as the lower sleeve and the

2 sleeve 24 as the upper sleeve, although it is understood that these terms are descriptive ones and not intended as terms of limitation.

The upper sleeve 24 is formed at its lower edge with a toothed clutch surface 25, adapted to co-operate with the toothed surface 23 on the sleeve 14 in a manner to effect a clutch connection therebetween, as will be hereinafter explained. Extending from the sleeve 24 are oppositely disposed pintles 26, upon which are mounted rollers 27, which latter are held in place by means of washers 28, the ends of the pintles being slightly upset or otherwise configured to hold the washers in place. These rollers travel within spiral slots 29 formed in a fixed bushing 30.

The rollers, as will be understood from the drawings, have a slight amount of play in the slots, so that in moving either up or down they engage only with one wall of the slots. Thus, the amount of friction between the rollers and the walls of the slot is very slight, which is advantageous in that there is no appreciable impedance offered to the normal movement of the valve by the application thereto of the rotating device, and the device can operate with very little lubricant. In fact, it is believed that no lubricant at all would be necessary to operation, although it would be advantageous.

Formed in the upper portion of the sleeve 24 is a recess 31, which receives a horseshoe-shaped washer 32. This washer is formed with a circular periphery 33 adapted to seat within the recess 31, so that it may rotate therein, and is provided with an elongated slot 34, the walls 35 of which engage with oppositely flattened portions 36 on the valve stem. The washer, seating as it does within the recess 31, cannot become displaced and is effective as a means for returning the sleeve 24 to lowered position upon downward movement of the valve stem, as will appear hereinafter.

It has previously been described how the valve stem 11 is connected to the sleeve 14 through the instrumentalities of the horseshoe washer 18, which seats within the recess 17 in the head 15, and is locked to the valve stem by engaging flattened surfaces thereon. The preceding paragraph discloses how the washer 32 is connected to the valve stem by simply forming flat spots on the latter. Thus, the parts which join the valve stem to the various portions of the rotator device consist of the two horseshoe washers 18 and 32, each of which are applied by merely grinding flattened surfaces on the valve stems at their point of application—a very simple manufacturing step. Moreover, substantial bearing surfaces are given to various connections, so that they are firmly held in position and are capable of efficiently performing their functions, and all of the

above advantageous results obtained without in any way weakening the valve stem.

The bushing 30 terminates in a head 36, which is held in position to the engine structure by a pin 37, or otherwise, so that said bushing remains fixed. By the use of the spiral slots and rollers, not only is friction overcome and ease of movement obtained, but these co-acting parts are exposed so that they become very readily lubricated by the vaporized oil within the valve chamber 7 and nothing else is needed to keep these parts in workable lubricated condition, especially as owing to the small surface contact between them, only slight lubrication is needed.

The operation is thought to be clear from the foregoing, but briefly is as follows: Upon contact of the lower end of the valve stem by the tappet rod, the said stem is lifted, and by reason of the key connection with the head 15, the sleeve 14 is advanced upwardly and the clutch surfaces 23 and 25 brought into clutching engagement. Further upward movement of the valve stem and the sleeve 14 also raises the sleeve 24. This causes an upward movement of the rollers 28 in the slots 29, and because of the helical formation of the slots, a turning movement is imparted to the sleeve 24. By reason of the clutch connection between this sleeve and the sleeve 14, the latter sleeve is turned, and this turning movement turns the head 15; and by reason of the key and recess connection between this head and the valve stem, the latter is rotated, giving the valve 12 a rotative movement. The advantages of such movement have been fully explained in my patents previously referred to and will not be detailed at this time. When the cam releases from the end of the tappet, a spring 38 acts to move the head 15 and sleeve 14 downward, breaking the clutch connection between the surfaces 23 and 25, and returning the sleeve 14, valve stem and valve to lowered position. The sleeve 24 is returned to lowered position by the washer 32 carried by the valve stem engaging with the lower wall of the recess 31, and thus the parts are returned to normal position, but with no rotative movement being imparted to the valve stem, since the clutch connection is broken between the sleeves 24 and 14, and the sleeve 24, being loose upon the stem, moves back to its lowered position without imparting a rotative movement to the stem.

While the device has been described with considerable particularity, it is not deemed to be limited in any other manner than by the terms of the appended claims.

I claim:

1. In a device of the class described, the combination of a valve stem, a valve secured to the stem, a lower sleeve, a head on the

- lower end of said sleeve, a non-circular recess in the under face of said head, a washer embracing the stem and having a transverse sliding and non-rotative engagement with 5 said stem, said washer resting in said head recess and having the periphery thereof of complementary configuration to the walls of the recess, the periphery of the washer and the walls of the recess co-operating to form 10 an interlocking non-rotative connection between said stem and sleeve, a sleeve loose on the stem, means for effecting a connection between said fast and loose sleeves upon movement of the stem, and means for im- 15 parting a rotative movement to said loose sleeve while said sleeves are connected, whereby a rotative movement is imparted to the stem during the movement thereof, sub- stantially as described.
- 20 2. In a device of the class described, the combination of a valve stem, a valve secured to the stem, a lower sleeve, a head on the lower end of said sleeve, a non-circular recess in the under face of said head, a washer 25 embracing the stem and having a transverse sliding and non-rotative engagement with said stem, said washer resting in said head recess and having the periphery thereof of complementary configuration to the walls of
- the recess, the periphery of the washer and 30 the walls of the recess co-operating to form an interlocking non-rotative connection be- 35 tween said stem and sleeve, means for effect- ing a connection between said sleeves upon upward movement of said stem, means for 40 imparting a rotative movement to the loose sleeve while said sleeves are connected, whereby a rotative movement is imparted to the valve stem, means for breaking said connection between said sleeves upon down- 45 ward movement of the valve stem, a washer intermediate the valve stem and embracing the stem, and having a transverse sliding and non-rotative engagement with said stem, the upper end of said loose sleeve being 50 formed with a recess in which said washer rests, said washer having a turning fit in said recess, and said recess being of suf- 55 ficient depth to prevent movement of the washer out therefrom during operation of the parts, said washer engaging the floor- ing of the recess and acting to move the loose sleeve downward when the parts return to normal position and after the connection between said sleeves has been broken, sub- stantially as described.

WILMER G. BUCK.
